CABINET FOR OFFICE COMMUNICATION APPARATUS

Edgar W. Breisch, Edgewood, Pa., assignor to The Union Switch & Signal Company, Swissvale, Pa., a corporation of Pennsylvania

Application February 11, 1946, Serial No. 646,736

3 Claims. (Cl. 175—298)

1

My invention relates to cabinets for office communication apparatus, and more particularly to cabinets for communication apparatus arranged in assemblies.

In communication systems the apparatus is generally arranged in assemblies. For example, in railway train communication systems the apparatus is generally arranged in a receiver assembly, a transmitter assembly and a power assembly. Each of these assemblies comprises a number of related devices mounted on a common frame or chassis and the assembly can be handled as a unit. Such assemblies have a relatively large number of circuit connections with outside circuits, and such outside circuit connections are frequently completed through a plug-in type of connector, one element of this connector being fixed on the portable assembly and the other unit being fixed in the cabinet in which the assembly is located. With such an arrangement each assembly has a definite assigned location in the cabinet. Many of the circuits associated with each assembly must be tested from time to time to check the operating condition of the circuits and to facilitate this testing the circuits should be made accessible for connecting testing instruments thereto. Confusion of the circuits is avoided if the wires can be kept in an orderly manner as they are run in the housing to the associated terminals of the assemblies. Also, time is saved in the original wiring of the housing when the wire channels are located to be convenient to the workmen. Furthermore, such assemblies function more quietly and with less static when each assembly is locked in place and vibration thereof is avoided.

Accordingly, a feature of my invention is the provision of a novel and improved cabinet for assemblies of communication apparatus and where-with the interior of the cabinet can be readily arranged to accommodate assemblies of different designs and dimensions and outside circuits of widely different characters can be segregated to avoid interference therebetween.

Another feature of my invention is the provision of a cabinet for apparatus of the type here involved incorporating novel means for locating the different assemblies of the apparatus at pre-selected locations in the cabinet and locating the terminals of the various circuits so as to be accessible for making the original connections and for maintenance testing.

Again, a feature of my invention is the provision of a communication apparatus cabinet incorporating improved means for bringing the wires of the circuits to designated terminals in an orderly manner.

2

Still another feature of my invention is the provision of a novel apparatus cabinet of relatively rugged structure, of neat appearance for office installation and of relatively simple and inexpensive construction.

Other features, objects and advantages of my invention will appear as the specification progresses.

To attain the foregoing features, objects and advantages of my invention, I provide a metal case of neat construction and the interior of which is such as to permit various arrangements of shelving for holding assemblies of different dimensions. A compartment at the bottom of the case serves as a space into which the lead wires of the outside circuits enter the cabinet. The terminals for receiving these outside lead wires are mounted in the front end of the cabinet and adjacent to both sides of a door frame, the terminal support being V-shaped with one leg welded to the inside of the case and the terminals mounted on the other leg so that the terminals face the door and are readily accessible for original connection of the wires thereto and for connecting an instrument for testing purposes. The problem of bringing the lead wires from the bottom compartment to these terminals is solved by making the door frames of channel shape and wide enough to serve as a wire chase and each individual wire can be readily brought up from the compartment to the terminal without special treatment, such as lacing of the wires. This position of the wires makes it easy for the workmen to put the wires in place. Also the wires are fully protected and are unexposed giving a neat appearance to the interior of the cabinet.

Each shelf is secured to a support welded to the inside of the cabinet and a shelving arrangement can be provided to accommodate assemblies of different dimensions with no change in the basic design of the case. Each shelf is of an inverted channel construction to give the shelf ample strength and at the same time provide a compartment underneath the shelf in which locking means can be secured. Supporting members are secured to the rear element of the shelf and these supporting members serve for mounting one unit of a plug-in type of connector. For example, the plug contact unit of such a connector would preferably be secured to such supporting member. Means at the back of the case and at each side serves to retain in place the wires run from the terminals of the connectors to corresponding terminals mounted near the door. This extra space at the back of each shelf also makes it possible for wires of special circuits, such as high frequency circuits, to be brought into the case

through special openings directly to the associated assembly, and thus avoid interference with the power and the control circuits brought into the compartment at the bottom of the case.

Each shelf is equipped with guide bars, interlocking plates and a worm wheel so that each assembly can be easily drawn into place to engage the units of the connector, and also to lock each assembly in place to avoid vibration. Conversely, such means aids in disengaging the connector when an assembly is to be removed. Furthermore, the interlocking means is such that only a unit or assembly of proper construction can be placed on that shelf.

I shall describe one form of cabinet embodying my invention and shall then point out the novel features thereof in claims.

In the accompanying drawings, Figs. 1 and 2 are front elevation and top views, respectively, showing one form of cabinet embodying my invention when used for office apparatus of railway train communication systems, the door of the cabinet being removed in Fig. 1. Fig. 3 is a view showing the mounting of the terminals of the cabinet of Figs. 1 and 2.

In each of the different views like reference characters designate similar parts.

It is to be understood that cabinets embodying my invention are not limited to use with railway train communication apparatus and this one uses serves to illustrate the many places such cabinets are useful.

Referring to the drawings, the reference character 10 designates a case of a cabinet and which case is preferably a rectangular sheet iron case of dimensions preselected suitable for the apparatus to be housed therein. A sub-base 11 of suitable material, such as stainless steel, is secured to the bottom of the case 10 and serves as a "mopping strip" to prevent damage to the cabinet when installed on the floor.

Directly above the sub-base 11 is a compartment 12 reserved for the incoming lead wires of the outside circuits associated with the apparatus housed in the cabinet. Two conduit hubs 13 are provided one at each side of the case to provide means for bringing the wires into the compartment 12 from either direction. A front panel 14 of the compartment 12 is secured in place by screws 15 and this panel can be readily removed and the interior of the compartment 12 exposed so as to facilitate the distribution of the wires to different wire channels to be described later, and with the panel 14 put back in place the criss-crossing of the wires is concealed to give a neat appearance to the interior of the cabinet.

The front of the case 10 is formed with a door frame 20, the vertical door jambs of which frame are shaped to form wire chases 21 and 22, one on each side of the door. An enclosing door 23 is retained in place through locating pins 24 and 25 fitting into holes in the top of the panel 14 and two latches 26 and 27 near the top of the cabinet. Thus this door 23 can be removed to provide access to the interior of the cabinet. Also the door is of such a width and height that the assemblies housed in the cabinet can be readily installed therein.

In the form of cabinet here disclosed, three shelves, a top shelf 16, a middle shelf 17 and a lower shelf 18, are provided. The shelves are alike and each is of an inverted pan shaped structure. That is, each shelf has a dependent portion on all sides making a relatively rigid construc-

tion and also providing a protected compartment below each shelf. Each shelf is bolted to a channel shaped support 19 welded to the inside of the case, there being one support at each end of the shelf. Each support 19 is made to extend out from the case a preselected distance to provide a space for carrying circuit wires along each end of the shelf. Each shelf is made of a length so as to slide easily into place between two supports 19. It is clear that with such a structure the spacing of the shelves can be readily arranged to accommodate different assemblies of different dimensions. That is to say, any specific shelving arrangement can easily be provided by proper positioning of the supports 19 and such arrangements can be made without any change in the basic design of the case 10.

A vertical support 28 is secured to the back member of each shelf. The top shelf 16 on which two receiving assemblies are located is provided with two such supports 28. Each support 28 carries one unit of a plug-in connector, each support 28 and its associated connector unit being located for the unit to mate with the other unit of the connector secured to the frame of the associated assembly.

Each shelf is equipped with interlocking plates, guide bars and a worm wheel for each assembly, the top shelf 16 having two sets of such devices 30 to take care of the two receiving assemblies located thereon. Looking at Fig. 2, two beveled guide bars 29 and 30, two interlocking plates 31 and 32, and a worm wheel 33 are provided for a first one of the receiving assemblies. The guide bars 29 and 30 are accurately welded to the shelf 16 and are beveled to fit two guide bars secured to the frame of the associated assembly and indicated at 34 and 35 in Fig. 1. The guide bars 29 and 30 secured to the shelf 16 are arranged in a 40 V-shaped pattern so that the assembly when slid into place on the shelf has its guide bars 34 and 35, also of a V-shaped pattern, mating and locking with the guide bars on the shelf when the assembly has reached its final position.

45 The two interlocking plates 31 and 32 are provided with slots 36 and 37 which mate with plates secured on the assembly frame. It is to be seen therefore that only assemblies having plates positioned properly to fit the slots 36 and 37 can be 50 mounted in this position on the shelf 16. It is to be observed that plates 38 and 39 for the other assembly mounted on shelf 16 have slots differently spaced from those of the plates 31 and 32 and thus with the interlocking plates of the different shelves and different assemblies arranged in a different order each assembly can be placed only in its proper place in the cabinet.

The worm wheel 33 is secured to a small shaft 40 journaled on the underside of the shelf 16, 60 the arrangement being such that the worm wheel extends up through an opening in the shelf to engage a rack fixed to the frame of the associated assembly. The outer end of the shaft 40 is formed with a head 41 to receive a socket wrench. 65 Thus when an assembly is to be housed the assembly can be slid onto the shelf with the guide bar of the assembly straddling with the guide bars on the shelf, if the interlocking plates of the assembly mate with the slots of the interlocking plates of the shelf. The assembly can be slid into place far enough for the rack of the assembly to engage the worm wheel 33. The worm wheel 33 is then turned through the wrench fitting onto the head 41 of the shaft 40 and the 70 assembly is drawn into its final place to connect 75

the units of the plug-in connector. At this final position, the guide bars are drawn into firm engagement due to their V-shaped pattern, and the assembly is locked against all vibration.

Control and power connecting wires from each connector secured to the back of a shelf are carried to terminals 47 located in a vertical arrangement just inside of the door frame of the same shelf. V-shaped metal strips 42 form terminal supports, one leg of each strip 42 being welded to the wall of the case 10 and the terminals 47 being mounted on the free leg of the strip. As shown in Fig. 3, each terminal 47 is preferably secured to the strip 42 through an insulation lock 43. The leads from the connector to the terminals are held in place and concealed through Z-shaped strips 44 screwed to the shelf support 19.

The wires of the outside circuits for an assembly are brought in through the compartment 12 in the manner explained hereinbefore, and the individual wires are brought up to the terminals 47 adjacent the shelf which holds the associated assembly through one or the other of the wire chases 20 or 21. The position of the wire chases 20 and 21 just inside the door and the position of the terminals 47 just inside the door make it easy to install the wires and at the same time the wiring is protected and almost entirely concealed.

Special openings 45 on each side of the case 10 are provided adjacent to the receiver and transmitter shelves and cable grips are inserted in these openings for bringing in cables from high frequency or special circuits. Each support 28 is provided with a special terminal 46 for receiving such high frequency cables and thus the high frequency circuits are brought into the proper assembly without interference with the control of power circuits.

A cabinet such as here disclosed has the advantages that all control and power lead wires enter through conduit hubs in a separate compartment at the bottom of the cabinet, vertical wire chases built into the frame of the door make it easy to run the wires to their terminals and the wires are protected and concealed, the supporting means for the individual shelves allow special arrangement of the shelving without a change in the cabinet case, the shelves are equipped with interlocking and locking features to assure that only proper assemblies can be placed on any shelf and the assembly can be easily drawn into place for engagement with the associated connector unit, an assembly can be readily disconnected for replacement by a new assembly, terminals supported vertically adjacent to each shelf and at the front near the door make it easy to wire the housing and to test the circuits, all wiring of the cabinet is largely concealed and protected, and high frequency connections are brought in where interference with the other circuits is avoided.

Although I have herein shown and described but one form of cabinet for office communication apparatus embodying my invention, it is understood that various changes and modifications may be made therein within the scope of the appended claims without departing from the spirit and scope of my invention.

Having thus described my invention, what I claim is:

1. In a housing for electrical apparatus assemblies, the combination comprising, a metal case, a pair of shelf supports secured to opposite inside

walls of said case, a shelf secured to said shelf supports, a vertical panel member secured to the rear flange of said shelf to mount one unit of a plug-in connector in a position predetermined with respect to said shelf, and a pair of interlocking plates secured to said shelf and each said plate having a slot disposed in a position predetermined with respect to the position of said one connector unit whereby assemblies provided with

5 interlocking plates can be slid onto said shelf for the other unit of said connector fixed on the assembly to engage said one connector unit only when the interlocking plates fixed on the assembly mate with said slots of said interlocking plates secured to said shelf.

10 2. In a housing for electrical apparatus assemblies, the combination comprising, a case having a shelf secured therein, means to mount one unit of a plug-in connector in said case in a position predetermined with respect to said shelf, and a pair of interlocking plates secured to said shelf and each said plate provided with a slot disposed in a predetermined position with respect to the position of said one connector unit whereby assemblies provided with interlocking plates and

15 having fixed thereon the other unit of said plug-in connector can be housed on said shelf in position for the connector units to engage each other only when such assembly is provided with interlocking plates that mate with said slots of the

20 interlocking plates secured to said shelf.

25 3. In a housing for electrical apparatus assemblies, the combination comprising, a case having a shelf secured therein, means to mount one unit of a plug-in connector in said case in a position predetermined with respect to said shelf, a pair of guide bars secured to said shelf in a V-pattern in a position predetermined with respect to the position of said one connector unit, said guide bars

30 formed with locking surfaces to engage locking surfaces of mating guide bars secured to an assembly when such assembly is slid onto said shelf for the other unit of said plug-in connector mounted on the assembly to engage with said

35 4. In a housing for electrical apparatus assemblies, the combination comprising, a case having a shelf secured therein, means to mount one unit of a plug-in connector in said case, a pair of interlocking plates secured to said shelf and each such plate having a slot disposed in a position predetermined with respect to the position of said one connector unit, whereby assemblies

40 provided with interlocking plates can be housed on said shelf for said connector units to engage and said guide bars to lock the assembly in place only when such assembly is provided with interlocking plates that mate with said slots of the

45 interlocking plates secured to said shelf.
